UNITED STATES PATENT OFFICE

139,172

DESIGN FOR AN AIRCRAFT TURN
INDICATOR

Lennox F. Beach, Port Washington, Orland E. Esval, Huntington, and Arthur W. Lane, Roosevelt, N. Y., assignors to Sperry Gyroscope Company, Inc., a corporation of New York

Application December 30, 1943, Serial No. 112,128

Term of patent 14 years

(Cl. D52—1)

To all whom it may concern:

Be it known that we, Lennox F. Beach, Orland E. Esval and Arthur W. Lane, citizens of the United States of America, residing at Port Washington, Huntington, and Roosevelt, respectively, in the counties of Nassau, Suffolk, and Nassau, respectively, and State of New York, have invented a new, original, and ornamental Design for an Aircraft Turn Indicator, of which the following is a specification, reference being had to the accompanying drawing, forming part thereof.

Fig. 1 is a front perspective view of an aircraft turn indicator showing my new design; and

Fig. 2 is a fragmentary top plan view of the indicator with a portion of the front wall thereof broken away. Two of the exposed glass areas and one of the exposed metal areas are represented in section in this view.

We claim:

The ornamental design for an aircraft turn indicator, as shown.

LENNOX F. BEACH,
ORLAND E. ESVAL,
ARTHUR W. LANE,
